UNITED STATES PATENT OFFICE.

THOMAS BENTON DORAN, OF PHILADELPHIA, PENNSYLVANIA.

WOVEN PILE FABRIC.

SPECIFICATION forming part of Letters Patent No. 773,130, dated October 25, 1904.

Application filed January 7, 1903. Serial No. 138,172. (No specimens.)

To all whom it may concern:

Be it known that I, THOMAS BENTON DORAN, a citizen of the United States, residing at Philadelphia, in the county of Philadelphia and State of Pennsylvania, have invented certain new and useful Improvements in Woven Pile Fabrics, of which the following is a specification, reference being had therein to the accompanying drawings.

- 10 My invention relates generally to woven pile fabrics, and more particularly to the class of such fabrics known as "three-shot" fabrics. In such three-shot fabrics three of the weft-threads are tied in each loop of the 15 binder warp-threads, and in such fabrics as heretofore there has been one tuft or loop of the pile-forming figuring warp-threads for each group of three weft-threads, and in such fabrics as heretofore made a threefold pile-forming figuring warp-thread has been usually employed. In Brussels or Wilton fabrics of the three-shot variety as heretofore made with the usual employment of threefold worsted for the pile-forming threads the 20 quantity of unused figuring warp-threads buried within the fabric has been very large—as, for example, with five sets of pile-forming figuring warp-threads there have been four threefold worsted threads buried in the 25 fabric for every tuft or loop of pile appearing on the surface of the fabric.

According to my invention one pile loop or tuft is provided for each weft-thread in the different plies of the fabric, and thus in each 30 group of three weft-threads of a three-shot pile fabric there will be three pile loops or tufts, and I may employ single-fold worsted and produce upon the surface of the fabric the same quantity of pile as has been produced in the three-shot fabric heretofore employed with threefold worsted. With single-fold worsted the quantity of buried worsted is reduced two-thirds, and therefore the embodiment of my invention effects a saving of 35 two-thirds of the buried or drag warp in a Brussels or Wilton fabric. The embodiment of my invention also effects a finer subdivision and a more even distribution of the surface-threads and also permits a finer arrangement of 40 pattern changes, thereby affording superior pattern effects, and also produces a fabric in

which by reason of the more uniform and even distribution of the surface-threads over the face of the fabric superior wearing qualities are attained. By reason of the tying of the 55 pile loops or tufts in all plies of the fabric and by each weft-thread thereof a very effective tying of these loops or tufts is attained and the durability and wearing qualities of the fabric are increased.

Many of the advantages of my invention may also be attained in various constructions of fabric—as, for example, the tying of the pile in both the upper and the lower plies, resulting in a tight tying, and in patterned 65 fabrics the exhibition of a pattern resembling the face pattern on the back of the fabric.

Many of the advantages of my invention may also be attained in a tapestry or velvet fabric—as, for example, the finer subdivision 70 of the pile and the more even distribution thereof and the superior binding or tying of the pile.

I will now describe the constructions of fabrics embodying my invention illustrated 75 in the accompanying drawings and will thereafter point out my invention in claims.

Figure 1 is a diagrammatic view illustrating a vertical longitudinal section of a portion of a Wilton or Brussels fabric during the process 80 of weaving the fabric. Fig. 2 is a similar view illustrating the same portion of the fabric after the pile has been cut or sheared to produce a Wilton fabric. Fig. 3 is a similar view of a cut or sheared velvet fabric. Figs. 85 4 and 5 are similar views of modified constructions of Wilton or Brussels fabric during the process of weaving.

Each of the drawings illustrates two successive sets of weft-threads and one of each of the 90 binder warp-threads, figuring warp-threads, and stuffer warp-threads in the several sets of such threads woven in the fabric. In the construction of fabric shown in Figs. 1, 2, and 3 the weft-threads are arranged in two 95 planes or layers or plies, and in the construction of fabric shown in Figs. 4 and 5 the weft-threads are arranged in three layers or planes or plies.

In the four fabrics shown the binder weft- 100 threads are arranged in sets of six weft-threads each, the several weft-threads in each set be-

ing designated by the numerals 1, 2, 3, 4, 5, and 6, respectively, and in each set of weft-threads there are two three-shot groups. In each group of three weft-threads in the constructions shown in Figs. 1, 2, and 3 the first weft-thread is in the upper ply, the second weft-thread in the lower ply, and the third weft-thread in the upper ply, and thus in each set of weft-threads the weft-threads 1, 3, 4, 10 and 6 are in the upper ply and the weft-threads 3 and 5 in the lower ply.

In the constructions shown in Figs. 4 and 5 the several shots of each group of three weft-threads are in different plies—the first in the 15 upper ply, the second in the middle ply, and the third in the lower ply, and thus in each set of weft-threads the weft-threads 1 and 4 are in the upper ply, the weft-threads 2 and 5 are in the middle ply, and the weft-threads 20 3 and 6 are in the lower ply. The binder warp-threads are designated *b* and *b'*, respectively, and are arranged in two sets interwoven with the weft-threads, and in the weaving of the fabric the binder warp-threads are 25 alternately and oppositely up for three shots of weft-threads and then down for three shots of weft-thread, so that in each set of six weft-threads each binder warp-thread is over one group of three weft-threads and under the 30 other group of three weft-threads. Thus the binder warp-thread *b* is over the weft-threads 1, 2, and 3 and under the weft-threads 4, 5, and 6 and the binder warp-thread *b'* is under the weft-threads 1, 2, and 3 and over the weft-threads 4, 5, and 6.

In the constructions of fabric shown in Figs. 1, 2, 4, and 5 the figuring warp-threads are shown as arranged in five sets and may be of different colors and are designated *c*, *d*, *e*, *f*, 40 and *g*, respectively. These figuring warp-threads are separately brought to the upper surface to form the pile, the threads unused at any place being buried in the fabric. In the two-ply fabric (shown in Figs. 1 and 2) 45 the unused pile-forming figuring warp-threads or drag warp-threads are between the upper and lower plies of the fabric. In the three-ply fabrics (shown in Figs. 4 and 5) the drag warp-threads are shown as divided above and 50 below the middle ply; but their arrangement may be varied as desired. The stuffer warp-threads are arranged at all times between the upper and lower plies of the fabric. Two sets of stuffer warp-threads are usually employed; but in two-ply fabrics these two sets 55 are controlled alike or as one set of double threads, and only one stuffer warp-thread is shown in Figs. 1, 2, and 3 of the drawings. In the three-ply fabrics shown the two sets 60 of stuffer warp-threads are divided above and below the middle ply, and in Fig. 4 the stuffer warp-thread *s* is shown as at all times above the middle-ply weft-threads 2 and 4, and the stuffer warp-thread *s'* is shown as at all times 65 below these middle-ply weft-threads, while in

Fig. 5 the stuffer warp-threads are shown as alternately and oppositely above and below the middle-ply weft-threads, thereby assisting to maintain the middle-ply weft-threads in proper position.

In Figs. 1, 4, and 5 a part of one of the pile-forming wires or bars *p* is shown in the position which it would occupy relatively to the fabric during the process of weaving the fabric, this pile-wire being arranged longitudinally of the fabric and the pile-forming figuring warp-threads being carried laterally over this longitudinal pile-wire in the formation of each pile-loop, and, as shown, the thread of the loop passes upward at one side of the 80 longitudinal pile-wire and downward at the other side thereof and then upward at the same side as that at which it passed down and then downward at the other side at which it originally passed up, so that at each alternate 85 loop a pile warp-thread passes over the pile-wire in the same direction. The fabric may be woven, however, with each loop of pile warp-thread passing over the pile-wire in the same direction. As shown, the pile-forming 90 figuring warp-thread *o* is tied by the first weft-thread 1 in the first set of weft-threads at the left of the drawings and passes under the weft-thread and up over the pile-wire, and then down through the fabric to the lower 95 face thereof and around the second weft-thread 2 of the set, and then upward through the fabric and over the pile-wire and then downward and under the third weft-thread 3 of the set and then upward and over the pile- 100 wire and then downward and around the fourth weft-thread 4 of the set, and then upward and over the pile-wire and downward through the fabric to pass under and be tied by the fifth weft-thread 5 of the set, and then upward 105 through the fabric and over the pile-wire and down under the sixth weft-thread 6 of the set of weft-threads, and then upward and over the pile-wire and downward to pass under and be tied by the first weft-thread 1 of the next or 110 second set of weft-threads shown in the drawings, and then over the pile-wire and down through the fabric and under the second weft-thread 2 of this second set of weft-threads and into the body of the fabric. The pile- 115 forming figuring warp-thread *d* now takes the place of the pile-forming figuring warp-thread *c* on the surface of the fabric and passes upward over the pile-wire and down under the third weft-thread 3 of the second 120 set of weft-threads, and then upward over the pile-wire and downward under the fourth weft-thread 4 of the second set of weft-threads, and thereafter as described relatively to the pile-forming figuring warp-thread *c*. It is of 125 course evident that any of the pile-forming figuring warp-threads may be brought to the surface to form any one of the pile loops or tufts.

In the velvet fabric shown in Fig. 3 but 130

one set of pile-forming figuring warp-threads is employed, as usual in such fabrics, and a single figuring warp-thread *h* is shown, and this thread may be of one color throughout its length to produce a single colored fabric, or it may be partly-colored to produce a patterned fabric, as is usual in velvet carpets. A stuffer warp-thread *s* is also shown.

In the weaving of the fabrics shown a loom having longitudinal pile wires or bars will be employed and the looping of the pile-forming figuring warp-threads over the longitudinal pile wires or bars may be accomplished in any well-known manner. In a Brussels or Wilton fabric the pile-forming figuring warp-threads would be controlled by a jacquard mechanism and the stuffer warp-threads could be controlled by the jacquard or by heddles or journals, and the binder warp-threads would preferably be controlled by heddles or journals. In the weaving of a velvet fabric or of a tapestry fabric, which would be exactly like the velvet, except that the pile-loops would be uncut, all of the weaving could be accomplished with heddles or journals. It is evident that in the various applications of my present invention modifications may be made in details of construction.

My present invention embodies broad features of invention covered by claims of my former patent, No. 695,015, dated March 25, 1902, and I hereby disclaim everything claimed in such patent.

What I claim, and desire to secure by Letters Patent, is—

35 1. A pile fabric comprising binder weft-threads and binder warp-threads and pile-forming figuring warp-threads, the binder weft-threads being arranged in sets of six weft-threads each and the binder weft-threads and binder warp-threads being interwoven to form a plurality of plies, and the pile-forming figuring warp-threads forming a pile composed of threads bound by each weft-thread 45 in the different plies of the fabric.

2. A pile fabric having an upper ply and a lower ply and comprising binder weft-threads and binder warp-threads and pile-forming figuring warp-threads, the binder weft-threads being arranged in sets of six weft-threads each, four weft-threads in the upper ply and two in the lower ply in each set, and the pile-forming figuring warp-threads forming a pile composed of threads bound by each weft-thread 55 in the different plies of the fabric.

3. A pile fabric comprising binder weft-threads and binder warp-threads and pile-forming figuring warp-threads, the binder weft-threads being arranged in sets of six weft-threads each and the binder weft-threads and the binder warp-threads being interwoven to form a plurality of plies and the pile-forming figuring warp-threads forming a pile projecting at one face only of the fabric, and the pile being composed of threads bound by each 65

weft-thread in the different plies of the fabric and extending outwardly to form the pile on each side of each weft-thread and on the pile-face only of the fabric.

4. A pile fabric having an upper ply and a lower ply and comprising binder weft-threads and binder warp-threads and pile-forming figuring warp-threads, the binder weft-threads being arranged in sets of six weft-threads each, four weft-threads in the upper ply and two in the lower ply in each set, and the pile-forming figuring warp-threads forming a pile projecting at the upper face only of the fabric, and the pile being composed of threads bound by each weft-thread in the upper and lower plies of the fabric and extending outwardly to form the pile on each side of each weft-thread and on the upper face only of the fabric.

5. A cut-pile fabric having an upper ply and a lower ply and comprising binder weft-threads arranged in sets of six weft-threads each, each set being composed of two groups of weft-threads with two weft-threads in one ply and one in the other ply in each group, and binder warp-threads arranged in two sets 90 and passing from ply to ply around each group of weft-threads, and of a plurality of pile-forming figuring warp-threads successively bound by each of the weft-threads at the upper and lower plies of the fabric.

6. A pile fabric having an upper ply and a lower ply and composed of binder weft-threads in sets of six weft-threads each, each set being composed of two groups of weft-threads with two weft-threads in one ply and one weft-thread in the other ply in each group, and binder warp-threads arranged in two sets and passing from ply to ply about each set of weft-threads, and of a plurality of pile-forming figuring warp-threads, bound in the pile-forming portions thereof by each binder weft-thread in the upper and lower plies, substantially as set forth.

7. A cut-pile fabric comprising binder weft-threads and binder warp-threads and pile-forming figuring warp-threads, the binder weft-threads being arranged in sets of six weft-threads each and the binder weft-threads and binder warp-threads being interwoven to form a plurality of plies and the pile-forming 115 figuring warp-threads forming a pile projecting at one face only of the fabric, and the pile being composed of threads bound by each weft-thread in the different plies of the fabric and extending outwardly to form the pile on each side of each weft-thread and on the pile face only of the fabric.

8. A cut-pile fabric having an upper ply and a lower ply and comprising binder weft-threads and binder warp-threads and pile-forming figuring warp-threads, the binder weft-threads being arranged in sets of six weft-threads each, each set being composed of two groups of weft-threads with two weft-threads in the upper ply and one weft-thread 130

arranged in sets of six weft-threads each, each set being composed of two groups of weft-threads with two weft-threads in the upper ply and one weft-thread in the lower ply in 30 each group, and of binder warp-threads arranged in two sets and passing from ply to ply so as to be looped about each group of binder weft-threads, and of pile-forming figuring warp-threads bound by each of the weft-threads at the upper and lower plies of the fabric, substantially as set forth. 35

11. A three-shot pile fabric having a plurality of plies and comprising binder weft-threads and binder warp-threads and pile-forming figuring warp-threads, the pile-forming figuring warp-threads forming a pile composed of threads bound by weft-threads in both the upper and the lower plies of the fabric in each group of three weft-threads. 45

In testimony whereof I have affixed my signature in presence of two witnesses.

THOMAS BENTON DORRAN.
